ASSIGNORS TO WESTINGHOUSE ELECTRIC & MANUFACTURING COMPANY, A COR-
PORATION OF PENNSYLVANIA.

TRIMMER MECHANISM.

Application filed February 20, 1924. Serial No. 694,163.

Our invention relates to trimming means for gear grinding wheels and more particularly to mechanisms for trimming the tooth contour forming wheels utilized in the 5 grinding of gear teeth.

It is among the objects of our invention to provide a trimmer mechanism which shall be of simple, compact and durable mechanical construction and which shall be applicable to the trimming of gear grinding abrasive wheels of any involute tooth form and for any pitch of gear tooth that it is desired to grind.

Other objects of our invention are to provide a trimmer mechanism which may be conveniently adjusted to accurately form or trim the abrasive wheel in a simple manner, which shall not require a skilled operator for its manipulation and adjustment, and 20 which shall embody the use of a single abrasive cutting tool such as a diamond, for trimming both faces of the abrasive wheel.

Various types of trimmer mechanism have been utilized for trimming abrasive wheels 25 employed for grinding gear teeth which function by means of engagement with a cam member of the shape of the gear tooth to be ground. One type of cam trimming device has embodied a relatively large cam 30 or template having an engaging surface of substantially involute curve shape and which was co-operatively engaged by an extensible pantograph frame structure that carried the trimmer to effect a reduction to the normal size of the gear tooth for which the abrasive wheel was adapted. This involved 35 a rather indirect functioning of the mechanism which resulted in inaccuracies.

Our present invention is directed to a device 40 for trimming gear grinding wheels which functions on the involute generating principle in which a point taken on a straight line, tangent to a circle or cylinder will generate an involute when the line is 45 moved angularly on the circle or cylinder while retaining its tangential position. We accomplish the trimming function by utilizing this principle in the shape of a cylindrical block having a support mounted thereon 50 in which the trimmer, such as a diamond, is set, and the abrasive wheel is trimmed to the correct form by oscillating the diamond on

the outer periphery of the cylinder while maintaining engagement of the diamond with the surface of the abrasive wheel. The 55 trimmer holder and cylindrical block are pivotally mounted on a base to adapt them for swivel movement through an arc of 180°, which permits of utilizing the same trimmer on both sides of the wheel.

In the accompanying drawing, constituting a part hereof, and in which like reference characters designate like parts,

Figure 1 is a view, partially in section and partially in elevation, of a trimmer 65 mechanism embodying the principles of our invention;

Fig. 2 is a view, partially in section and partially in elevation taken along the line II-II of Figure 1,

Fig. 3 is a top plan view thereof, and

Fig. 4 is a fragmentary view, partially in section and partially in elevation showing the manner of securing the trimmer holder to the base cylinder.

Referring to Fig. 1, the structure therein illustrated comprises a base 1 having openings 2 by which it is adapted to be secured to a grinding machine. The base 1 is provided with a central opening 3 and a counter bore 4 that is adapted to receive a central projecting portion 5 of a center plate 6. The center plate 6 is provided with an opening 7 which registers with the opening 3 of the base 1, and a bolt 8 is projected therethrough to pivotally secure the center plate on the base 1. A saddle block 9 is slidably mounted on the center plate 6 by means of a screw shaft 10 on the plate 6 and having threaded engagement with a depending portion 11 of the saddle 9. The end of the screw 10 is extended through an opening 12 of the center plate 6, and is provided with a ring 13 that is secured thereto, to restrain axial movement of the shaft 10, and to permit rotational movement thereof.

The saddle block 9 is provided with a cylindrical portion 14 having a magnet coil 15 disposed thereon and insulated therefrom by suitable insulating material 16. Cylindrical segments 17 and 18 are secured to the respective sides of the block 9 by means of bolts 20. A grid member 21 having a handle portion 22 and a central grid 23 (Fig. 3), is

mounted on the segments 17 and 18 by means of a plurality of straps 24, (Fig. 4) one end of each strap being secured to the cylindrical segments and the other end to the grid member.

- 5 The straps 24 are preferably of non-ferrous substance, such as copper or phosphor-bronze, preferably the latter. The object of fastening the grid 21 by the straps 24 to the 10 cylindrical segments as shown, is to permit oscillatory movement of the handle 22 so that a point taken on the horizontal axis of the grid member will describe an involute curve when the handle 22 is actuated. A 15 trimmer 26, such as a cutting diamond properly set in an adjustable holder, such as a set screw 27, is secured in the center of the member 23 and is provided with a lock nut 28 to maintain adjustment of the screw 27. 20 A centering block 29 of hardened steel or other suitable material is secured to the segments by screws 30 and the relative position of the trimmer 26 and the abrasive wheel 32 to be trimmed is adjusted by bringing said 25 trimmer in engagement with the center block 29.

The center plate 6 is provided with a shoulder 33 to act as a stop for the extended base portion 34 of the saddle 9. When the 30 shoulder 33 and the portion 34 of the saddle are in engagement, the edge 37 of the center block 29, the center of the segments 17 and 18, and the centerline of the center plate 6 are all in the same vertical plane. An adjustment gage 35, that is equal in thickness to one half of the chordal distance between the intersection of the involute curves of the two sides of the grinding wheel and the base circle of said involute curves, is inserted between the shoulders 33 and 34. The diamond point 26 is set against the face 37 of the center block 29 with the grid in a horizontal position. The extension 40 of the saddle 9 limits the movement of the grid 21 so 45 that when the grid engages the extension 40, it is in a horizontal position.

The segments 17 and 18, and the straps 24 are so proportioned that the radius of the segments plus half the thickness of the 50 straps 24 constitutes the radius of the base circle of the tooth form to be generated on the wheel 32. The abrasive diamond 26 is set centrally with the center of the straps 24 and the grinding wheel 32 is adjusted relative thereto to obtain the proper chordal distance on the periphery of the wheel when the trimmer operates.

With the grid 21 in a horizontal position, the diamond or trimmer 26 is brought into 60 engagement with the block 29 by adjusting the screw 27 and it is then in working position to trim or dress the rotating wheel 32 by actuating the handle 22 of the grid. The oscillatory angular movement of the grid 65 handle produces a rolling motion of the grid

21 causing the trimmer 26 to describe an involute curve that is reproduced on the abrasive wheel 32.

After trimming one side of the wheel, the center plate 6 and the saddle block 9 are rotated 180° on the pivot bolt 8 and the operation is repeated by bringing the trimmer 26 into engagement with the other surface of the abrasive wheel.

During the trimming operation the magnet 15 is energized to set up a flux in the cylindrical member 43 which passes through the side portions of the grid 21, thus tending to attract the latter to provide the necessary contact with the segments 17 and 18 and the non-ferrous strips 24 act as insulating liners to prevent binding of the grid and segments.

It is evident from the foregoing description of our invention that a trimmer mechanism made in accordance therewith provides a simple and efficient means for accurately trimming and forming the involute faces of abrasive wheels for grinding gear teeth, and a further advantage is obtained by making the trimmer mechanism rotatable on its base so that the trimmer may be used on both sides of the wheel. The use of the same trimmer for both faces of the wheel produces the same degree of accuracy on both cutting faces of the grinding wheel which is a desirable condition for the reason that it results in uniform tooth profiles on the ground gear wheels.

Although we have described a specific embodiment of our invention, it will be obvious to those skilled in the art that various modifications may be made in the details of construction and the design and proportions of the several cooperating parts comprising our trimmer device, without departing from the principles herein set forth.

We claim as our invention:—

1. A trimmer mechanism for abrasive wheels comprising a base member, a plurality of cylindrical segments mounted thereon, means for turning said segments relative to said base member, a grid member mounted on said segments, a trimmer secured to said grid and means for rolling said grid on said segments.

2. A trimmer mechanism for abrasive wheels comprising a base member, a plurality of cylindrical segments secured thereto, a grid member mounted on said segments, a trimmer secured to said grid and means for rolling said grid on said segments, said means comprising a plurality of straps secured to said grid and segments.

3. A trimmer mechanism for abrasive wheels comprising a base member, a plurality of cylindrical segments secured thereto, a grid member mounted on said segments, a trimmer secured to said grid and means for rolling said grid on said segments, said

means comprising a plurality of straps secured at one of their ends to said segments and at their other ends to said grid.

4. A trimmer mechanism for abrasive wheels comprising a base member, a plurality of cylindrical segments adjustably secured thereto, a grid member mounted on said segments, a trimmer secured to said grid and means for rolling said grid on said segments, said means comprising a plurality of straps secured to said grid and segments.

5. A trimmer mechanism for abrasive wheels comprising a base member, a plurality of cylindrical segments secured thereto, means for adjusting said segments relative to said base member, a grid member mounted on said segments, a trimmer secured to said grid, means for rolling said grid on said segments, and means for holding said grid against the segments.

6. A trimmer mechanism for abrasive wheels comprising a base member, a plurality of cylindrical segments secured thereto, a grid member mounted on said segments, a trimmer secured to said grid, means for rolling said grid on said segments, and magnetic means for holding said grid against the segments.

7. A trimmer mechanism for abrasive wheels comprising a base, segments secured thereto, a grid mounted on said segments, a trimmer secured to said grid, magnetic means for holding said grid against said segments and non-ferrous straps secured to the grid and segment members.

8. A trimmer mechanism for abrasive wheels comprising a base, segments secured thereto, a grid mounted on said segments, a trimmer secured to said grid, magnetic means for holding said grid against said segments, non-ferrous straps secured to the grid and segment members, and adjusting means for said trimmer.

9. A trimmer mechanism for abrasive wheels, comprising a base, segments secured thereto, a grid mounted on said segments, a trimmer secured to said grid, magnetic means for holding said grid against said segments, non-ferrous straps secured to the grid and segment members, and means for adjusting said trimmer relative to said grid.

10. A trimmer mechanism for abrasive wheels comprising a base, segments secured thereto, a grid mounted on said segments, a

trimmer secured to said grid, magnetic means for holding said grid against said segments, non-ferrous straps secured to the grid and segment members, means for adjusting said trimmer relative to said grid and means for adjusting said grid relative to the said base.

11. A trimmer mechanism for abrasive wheels comprising a base, a cylindrical block pivotally mounted thereon, a plurality of segments secured to said block, a grid member mounted on said segments, straps secured at their ends to said grid and segments, a trimmer adjustably mounted in said grid, a magnet coil in said block, means for energizing said coil to establish a magnetic field in said segments and grid, adjusting means for said block relative to said base and means for rotating said block 180°.

12. A trimmer mechanism for abrasive wheels comprising a base, a plurality of segments mounted on said base, a grid member oscillatably mounted on said segments, straps secured to said grid and segments, and a trimmer mounted in said grid, said segments having a radius equal to the radius of the base circle less half the thickness of said straps.

13. A trimmer mechanism for abrasive wheels comprising a pivotal base, a plurality of segments mounted on said base, a grid member oscillatably mounted on said segments, straps secured to said grid and segments, and a trimmer mounted in said grid, said segments having a radius equal to the radius of the base circle less half the thickness of said straps.

14. A trimmer mechanism for abrasive wheels comprising a base, a plurality of segments removably mounted on said base, a grid member oscillatably mounted on said segments, straps secured to said grid and segments and a trimmer mounted in said grid, said segments having a radius equal to the radius of the base circle less half the thickness of said straps, and the generating surface of said trimmer being part of a circular cylinder.

In testimony whereof, we have hereunto subscribed our names this 13th day of February, 1924.
